UNITED STATES PATENT OFFICE.

WILLIAM S. SULLIVAN, OF CINCINNATI, OHIO, ASSIGNOR TO THE SULLIVAN PRINTING WORKS COMPANY, OF CINCINNATI, OHIO, A CORPORATION OF OHIO.

DESIGN FOR A DAILY CALENDAR OR SIMILAR ARTICLE.

Application filed May 18, 1928. Serial No. 26,733. Term of patent 7 years.

To all whom it may concern:

Be it known that I, WILLIAM S. SULLIVAN, a citizen of the United States of America, and a resident of Cincinnati, in the county of Hamilton and State of Ohio, have invented a new, original, and ornamental Design for a Daily Calendar or Similar Article, of which the following is a specification, reference being made to the accompanying drawing, forming part thereof.

The figure is a perspective view of a daily calendar or similar article embodying the design of the invention.

I claim:

The ornamental design for a daily calendar or similar article as shown.

WILLIAM S. SULLIVAN.
